UNITED STATES PATENT OFFICE

CLIFTON V. RATHER, OF SAN FRANCISCO, CALIFORNIA

GAME

Application filed May 11, 1931. Serial No. 536,397.

My invention relates to improvements in games wherein an inclined member is provided with a plurality of open bottomed pockets at the lower end thereof to receive balls deposited at the upper end of said inclined member, each of said pockets being provided with at least one side opening thru which a second ball is ejected by a first ball therein, said pockets operating in conjunction with a barrier slidably mounted in connection with said pockets and normally operating to prevent the passage of balls thru said open bottoms, said barrier being also provided with means actuated by the presence of a ball in any pocket to actuate an indicator for said pocket and thereby indicate the presence of said ball in said pocket, and to indicate a definite game-value of said occupied pocket.

20 The primary object of the present invention is to provide a new and improved game.

Another object is to provide a new and improved game wherein a given number of balls are deposited in one end of the game apparatus and rolled into certain pockets, and having improved means for returning duplicate deposits in any pocket to the player.

30 A further object is to provide a new and improved game of the character described, which shall be easily manipulated by one or more players from one end of the device.

A still further object is to provide a new and improved game wherein a plurality of differently valued indicators may be automatically operated to indicate the value of certain plays.

35 A still further object is to provide new and improved means for automatically returning duplicate deposits in any one pocket, as well as the total number of balls, to the players' end of the apparatus and simultaneously clearing the indicator of the score of the last play.

I accomplish these and other objects by 40 means of the device disclosed in the drawings forming a part of the present application, wherein like characters of reference are used to designate similar parts throughout the specification and drawings, and in which—

50 Fig. 1 is a broken plan view, partly in sec-

tion, disclosing my improved game apparatus;

Fig. 2 is a vertical longitudinal sectional view of the device;

Fig. 3 is a broken front elevation of the indicators;

Fig. 4 is a broken transverse sectional view of the pockets, and barrier; and

Fig. 5 is an enlarged broken detailed view of the indicator actuating means.

Referring to the drawings the numeral 1 is used to designate in general a housing having an inclined member 2 in the upper portion thereof, said member 2 being provided at the lower end thereof with a plurality of open bottom pockets 3, preferably arranged in staggered rows, as indicated in Fig. 1 of the drawings. Each pocket 3 is provided with at least one side opening 4, inner rows of pockets, where a plurality of rows is provided, depending below adjacent outer pockets to permit the provision of said side openings.

50 A barrier 6, consisting of a plurality of transverse bars 7, each arranged under each row of pockets 3, as disclosed in Figs. 1 and 2 of the drawings, is slidably mounted in connection with the pockets 3, by means of guide-ways or supports 8. A longitudinally disposed bar 9 is pivotally connected at one end to said barrier 6, as at 11, and has its opposite end extending exteriorly of the housing 1 at what I term the players' or depositing end of said housing 1, and is furnished with a suitable button 12, to facilitate 55 operation thereof.

The bar 9 is provided with a notch 14 with in which rests a spring 16 mounted upon a lateral support 17 mounted transversely of the housing 1, said spring 16 being positioned so that its tension will retain the barrier 6 and bars 7 thereof normally in a position to prevent the passage of balls 18 thru the bottom of the said pockets 3 but will not prevent a second ball deposited in any pocket from passing out of its respective side opening 4.

60 A second inclined member 19, oppositely inclined from the inclined member 2, is arranged in the lower portion of the housing 100

1 and below the pockets 3 and barrier 6, and has an exteriorly extending extension 21 at the depositing or players' end of said housing 1, the purpose of which will hereinafter 5 be more fully set forth.

Extending somewhat above the housing 1 and at the opposite end from the players' end of the housing 1 I have provided a plurality of differently valued or numbered indicators 10 22, each consisting of a numbered circle on glass or other transparent material 23, and behind each numbered circle 22 I have provided a cylindrical member 24 containing a lamp 26, so that when any one lamp 26 is 15 lighted as hereinafter set forth, it will illuminate its own particular numbered circle 22 and no other.

Mounted upon each transverse bar 7 of the barrier 6 and directly below each pocket 20 3, I have provided a pair of electrical contacts 27 which are suitably connected to a source of electrical energy 28, such as dry cells or the like, which may be mounted within the housing 1, by means of suitable wires 25 or conductors 29, each separate lamp or indicator being connected to a separate pocket 3.

A suitable glass cover 31 is mounted over the top of the housing 1 and the inclined member 2 in the upper portion thereof, and has one end arranged to fully enclose the entrance to the pockets 3 at the lower end of said member 2, and its opposite end arranged in spaced relation to the players' end of the 30 35 device, to form an opening to permit the deposit of the balls 18 upon the upper end only of said inclined member 2.

In operation, a given number of balls 18, as required by the rules of the game, as, for 40 instance, five, are deposited, one at a time, thru the opening above mentioned at the players' end of the device.

Thru the attraction of gravity each ball 18 rolls down the inclined member 2 and falls 45 into a pocket 3 and resting upon the contacts 27 on the adjacent bar 7, closes the circuit thru the wires or conductors 29 and battery 28 and thereby illuminates the lamp 26 back of the indicator 22 corresponding to 50 that pocket into which the ball 18 has been deposited, thereby indicating the value of that particular play.

As the remaining balls 18 are rolled into 55 different pockets 3 they in turn operate respective indicators 22 for the pockets entered and the totals of said numbered circles are added to produce the final score. As is usual in such games, the highest total score is the winning score.

Should one of the balls for an individual 60 play enter a pocket 3 already occupied by a previously deposited ball 18, such second ball will be ejected thru the side opening 4 by said first mentioned ball, and drop upon 65 the oppositely inclined member 19 and roll

exteriorly of the housing 1 to the players' or operator's end of the housing 1, to be there recovered and redeposited until it enters an unoccupied pocket.

After all of the balls deposited by any one 10 player have moved into separate pockets 3 and the total obtained, all of said balls are released from their respective pockets by pushing inwardly the bar 9 against the tension of the spring 16 thereby moving the 15 bars 7 away from the open bottoms of the pockets 3, as indicated in dotted lines in Fig. 2 of the drawings, thereby permitting all of the balls within said pockets 3 to drop upon the upper end of the oppositely inclined 20 member 19 and roll to a point exteriorly of the housing 1 and at the players' or depositor's end thereof where they will be recovered and redeposited for the next play.

When the balls 18 are released from their 25 respective pockets the contacts are permitted to resume their normally open position and the indicators 22 are de-energized or rendered inoperative and the score cleared.

Having thus described my invention, what 30 I claim as new and desire to secure by Letters Patent is—

1. A game comprising an inclined member provided with a plurality of pockets having open bottoms to permit the passage of a ball thru any of said pockets; a common barrier normally closing said open bottoms; an indicator for each pocket; means mounted upon the barrier adjacent each pocket and actuated by a ball therein for operating each 35 respective indicator to indicate the presence of said ball in said pocket; and means for shifting the barrier to release any balls in any pocket.

2. A game comprising an inclined member provided with a plurality of pockets having open bottoms to permit the passage of a ball therethru; a common barrier slidably mounted in connection with said inclined member and normally preventing passage of a ball thru said pockets; a separate indicator for each pocket; means mounted upon the barrier opposite each pocket and connected to its respective indicator and actuated by a ball within said pocket to operate said respective indicator; and means for moving the barrier to release balls thru the open bottoms of said pockets.

3. A game comprising an inclined member provided with a plurality of pockets arranged in rows and having open bottoms to permit the passage of a ball thru any of said pockets; a barrier slidably mounted in connection with said inclined member and comprising a plurality of bars, each bar being arranged below each row of pockets to prevent the passage of a ball thru any of said pockets; a separate indicator for each pocket; separate means mounted upon each bar opposite the open bottom of each pocket and

connected with its respective indicator and actuated by a ball within said pocket to operate said respective indicator; and means for moving said barrier to permit the passage of balls thru the pockets.

4. A game comprising an inclined member provided with a plurality of pockets having open bottoms to permit the passage of a ball thru said pockets, each of said pockets also having an open side whereby a second ball passing thereinto may be ejected thru said open side by a single ball within said pocket; a common barrier normally closing said open bottoms; an indicator for each pocket; separate means mounted upon the barrier opposite each pocket and connected to its respective indicator and actuated by a ball within said pocket to operate said respective indicator; and means for moving the barrier to release any balls remaining within any pockets.

5. A game comprising a housing having an inclined member therein provided with a plurality of pockets arranged in a plurality of rows, and having open bottoms to permit the passage of balls thru said pockets, certain of said rows of pockets depending below adjacent rows, and all of said pockets being provided with at least one open side whereby a second ball deposited within any pocket may be ejected thru said open side by a first ball therein; a common barrier slidably mounted within the housing and comprising a plurality of bars arranged opposite the open bottoms of each row of apertures; a separate indicator mounted upon the housing for each pocket; separate means mounted upon the bars, one for each pocket and connected to its respective indicator and actuated by a ball within said pocket to operate said respective indicator; and an oppositely inclined member arranged within the housing and below the pockets and barrier to return balls from said pockets.

45 6. A game comprising a housing having an inclined member in the upper portion thereof provided with a plurality of pockets arranged in rows and having open bottoms and at least one side opening whereby a second ball dropped into said pocket may be ejected by a first ball therein; a numbered indicator for each pocket; a barrier consisting of a plurality of bars arranged across the open bottoms of each row of pockets to normally prevent the passage of balls therethru; separate means mounted upon the bars for each adjacent pocket and connected with its respective indicator and actuated by a ball within said pocket for operating its respective indicator; means for moving the barrier to release all balls from their respective pockets; and an oppositely inclined member arranged below the pockets and barrier to return released balls exteriorly of the housing.

7. The combination with a game comprising a plurality of pockets to receive balls, of pockets having at least one side opening to release a second ball passing into said pocket before a first ball is released.

8. The combination with a game comprising a housing having an inclined member provided with a plurality of open bottomed pockets at the lower end thereof to receive balls deposited into the housing at the upper end of said inclined member, of pockets having at least one side thereof open to release a second ball passing into said pocket before a first ball therein is released; and means for automatically returning said released second balls exteriorly of said housing and at the depositing end thereof to facilitate the redepositing of said released second balls.

In witness whereof, I hereunto set my signature.
